UNITED STATES PATENT OFFICE.

CHARLES W. RONSHEIMER, OF PENNGROVE, CALIFORNIA.

BROODER HEATER.

Application filed October 2, 1925. Serial No. 60,090.

This invention relates to improvements in brooder heaters and has particular reference to a heater capable of use with illuminating gas or other similar gaseous fuels.

5 The principal object of this invention is to produce a brooder heater which will use a minimum amount of fuel and give off a uniform heat.

Another object is to provide means where-
10 by the heat is reflected laterally thereby se-
curing the greatest efficiency from the
amount of fuel employed.

A still further object is to produce a heater of this character which is simple in
15 construction and, therefore, cheap to man-
ufacture.

An additional object is to produce a heater of this character which may be substi-
20 tuted for the type of brooder heater now
used, without materially altering the con-
struction of the brooder house and other
equipment.

Other objects and advantages will be ap-
25 parent during the course of the following
description.

In the accompanying drawings forming a
part of this specification, and in which like
numerals are employed to designate like
parts throughout the same,

30 Figure I is a vertical cross section of my
improved heater,

Figure II is a front elevation of my heater,
showing the movable canopy partly
broken away, and

35 Figure III is a top plan view of the re-
flector cone.

Many types of brooder heaters are now
employed, which use various types of fuel.
These heaters are expensive to operate due
40 to the fact that a large percentage of the
heat rises and passes out of the stack with
a consequent loss. I have, therefore, de-
vised a heater whereby an exceedingly small
45 flame comparative to the size of the heater
suffices to maintain the required temperature
beneath the canopy and by referring to the
drawings, it will be noted that the numeral
5 designates a base having a plurality of
openings 6 therein.

50 The base 5 has a central opening 7 which
communicates with the interior of an in-
verted frustum of a cone 8 open at both
ends and forming an air chamber. In the
wall of this chamber 8 is formed a door
55 opening at 11. Mounted upon this chamber
8 is an element consisting of an inverted

frustum of a cone also open at both ends
and forming a combustion chamber 12 with-
in which a burner 13 is positioned.

This burner may be of any type capable 60
of heating a reflector cone 14 which is pro-
vided with a flange 16 which flange rests
upon the top of the combustion chamber 12.
This flange 16 is provided with a plurality
of holes 17 (see Figures I and III). 65

A dome 18 is superimposed upon the
whole structure and secured thereto in any
convenient manner. This dome has an out-
let 19, through which a pipe 21 passes.
This pipe extends downwardly to a point in 70
close proximity to the bottom of the re-
flector cone 14. This cone is lined with a
retort cement 22, the purpose of which will
be later seen.

This dome 18 is also covered with a coat-
ing of cement as shown at 23. A canopy
24 is slidably supported upon the stack 21
as is best illustrated in Figure II, and is
capable of being raised and lowered to ac-
commodate for chicks of various ages. 80

The operation of my heater is as fol-
lows:—

When the fuel supply is turned on and
admitted to the burner 13, the same is ig-
nited through the door 11. The flame im-
pinges upon the reflector cone 14, heating
the same, which heat is reflected against the
interior wall of the combustion chamber 12.
Fresh air is drawn through the openings 6
as indicated by the arrows which air passes 90
upwardly through the air chamber 8 coming
into contact with the hot surface of the
reflector cone 14, where it is heated to a
high temperature. This air then passes
through the openings 17 as indicated by the 95
arrows, downwardly within the cone and
upwardly through the stack 21. The result
of this construction is that heat is reflected
against the sides of the casting 12 on ac-
count of the fact that the cone is lined with 100
retort cement, the stored up heat is consider-
able, which heat is sufficient to maintain an
even temperature beneath the canopy.

This is an important feature, as it often
occurs that a sudden change in outside tem-
perature is injurious to the chicks and it
is, therefore, important that the heater
maintain as even a temperature as possible,
under all conditions, which is not possible
with a sheet iron or cast iron heater, as the 110
same lose their heat rapidly.

It is to be understood that the forms of

my invention herewith shown and described are to be taken as preferred examples of the same, and that various changes in the shape, size and arrangement of parts may be resorted to without departing from the spirit of the invention or the scope of the subjoined claim.

Having thus described my invention, I claim:—

- 10 In a brooder heater, a base having a plurality of openings therein, a circular casting forming an air chamber positioned on said base, the interior of said air-chamber communicating with the interior of said base, a second circular casting forming a combustion

chamber positioned on said first mentioned casting, a reflector positioned in said combustion chamber and having a plastic lining formed therein, means for heating said reflector and said lining for the purpose of 20 storing and reflecting heat to the wall of said combustion chamber, a dome positioned above said reflector and secured to said second mentioned casting, said dome having a plastic lining, and a pipe passing through 25 said dome and extending to a point in close proximity to said reflector.

In testimony whereof I affix my signature.

CHARLES W. RONSHEIMER.
